UNITED STATES PATENT OFFICE

102,559

DESIGN FOR A BATHTUB

Walter J. Kohler, Kohler, Wis., and Gerald K. Geerlings, New Canaan, Conn.

Application September 2, 1936, Serial No. 64,694

Term of patent 14 years

To all whom it may concern:

Be it known that we, Walter J. Kohler, a citizen of the United States, residing at Kohler, in the county of Sheboygan and State of Wisconsin, and Gerald K. Geerlings, a citizen of the United States, residing at New Canaan, in the county of Fairfield and State of Connecticut, have invented a new, original, and ornamental Design for Bath Tubs, of which the following is a specification, reference being had to the accompanying drawing, forming part thereof.

The figure is a perspective view of a bath tub showing our new design.

We claim:

The ornamental design for a bath tub, as shown.

WALTER J. KOHLER.
GERALD K. GEERLINGS.
